UNITED STATES PATENT OFFICE.

FREDERICK E. GREENE, OF NEW HAVEN, CONNECTICUT, ASSIGNOR TO THE ENGLISH
& MERSICK CO., OF NEW HAVEN, CONNECTICUT, A CORPORATION.

DESIGN FOR A REGULATOR HANDLE.

Application filed October 8, 1924. Serial No. 10,996. Term of patent 3½ years.

To all whom it may concern:

Be it known that I, FREDERICK E. GREENE, a citizen of the United States, residing at New Haven, in the county of New Haven and State of Connecticut, have invented a new, original, and ornamental Design for a Regulator Handle, of which the following is a specification, reference being had to the accompanying drawing, forming part thereof.

Fig. 1 is a plan view of a regulator handle showing my design.

Fig. 2 is a perspective view of the shell of a handle, showing my design.

I claim:

The ornamental design for a regulator handle as shown.

FREDERICK E. GREENE.
